SEAM MECHANISM FOR CAN DOUBLE
SEAMERS

William B. Peterson, Jr., Long Beach, and George G. Koeberle, Arcadia, Calif., assignors to Angelus Sanitary Can Machine Co., Los Angeles, Calif., a corporation of California

Application December 24, 1951, Serial No. 263,051

6 Claims. (Cl. 113—23)

1

This invention relates in general to can seaming mechanisms, and is particularly useful on can double seamers in which a can end is applied to a can body by a two-stage seaming operation.

The type of double seamer which the present invention is particularly adapted to be associated with is called a "can spin" machine, in that the can is rapidly rotated in the machine and the seaming operation is performed by the application to the rim of the can end of two seaming rolls which come into place successively to form a seam between the can end and the can in two stages or seaming operations. The can spin machine ordinarily embodies a slowly rotating turret having three or more devices for revolving the can end and can to perform the double seaming operation. Each of these devices is provided with a seaming chuck to engage the can end from above and fit within the panel thereof while the can body is lifted from beneath to fit into the can end, so that, while the seaming operation is being performed, the can body and can end will be properly related to be united by said operation.

The two seaming rolls for performing the two stages in the seaming operation are pivotally mounted on the ends of arms attached to the lower ends of vertical shafts journaled in the turret adjacent each of the can rotating devices, and arms on the upper ends of said shafts follow separate cams, which are approximately concentric with the axis of the turret and are stationary, to swing the seaming rolls successively into seaming relation with the can being rotated.

After a can is received by each of said devices, it is clamped between an elevator below the can and a chuck above the can, rotated by the chuck, subjected successively to the two seaming operations, and discharged from the seamer, all during a single revolution of the turret. The first stage in a double seaming operation is referred to as the "curling" operation, inasmuch as it terminates with the rim of the can end and the flange of the can body curled downwardly and inwardly together in an interlocking relation. The second stage of double seaming is referred to as the flattening and tightening operation, which term is descriptive of the action of the second seaming roll as it flattens and tightens the interlocked layers of the can end rim and can body flange to form a tight seal between the can body and can end.

In general, the can bodies are formed of a single piece of sheet metal rolled into cylindrical form and, with its adjacent edges interlocked in a straight seam extending from end to end of the body, and the end edges of this cylinder are then

2

rolled outwardly to form end flanges on the body which interengage with the can ends in the seaming operations by which the two can ends are applied to the can body. The first can end is applied, of course, in forming the open can and the second can end is applied, after the open can has been filled with product, to enclose said product in the can. As the interlocked straight seam of the can body has several layers of the material of the body in overlapping relation, it is substantially thicker than the rest of the can body, and this thickness where the straight seam extends into the can body flanges produces an excessive thickness in the seam formed between the can body and each can end.

In order for the second operation seaming roll to do a good job of flattening the curled seam formed in the first operation, it must be set to operate at a radius which brings it into conflict with the thickened portion of the seam where the roller must pass over the straight can body seam, and it is necessary to resolve this conflict by mounting the second operation roller yieldably so that it will yield to a greater radius relative to the can when it passes over said thickened portion of the seam, and then immediately return to its normal operating radius. It has been the practice heretofore to supply individual yieldable mountings for each of the second operation seaming rolls and, where a double seamer has as many as six or eight can rotating devices, it means it is necessary to effect a similar number of adjustments in these yieldable mountings of the second operation rolls. To attain the desired uniformity and pressure of these rolls in their second seaming operations, therefore, involves considerable labor.

It is an object of the present invention to provide in a double can seamer a means for applying a uniform yieldable pressure to the second operation seaming rolls associated with all the can rotating devices which can be varied by a unitary adjustment.

In the operation of a double seamer, it is necessary from time to time to inspect the curled joints produced by the first operation seaming rolls. Heretofore this has been a difficult and time-consuming operation, requiring the backing off of each of the arms carrying the second operation rollers so as to prevent the latter from performing their second seaming operation on the cans which it is desired to run through the machine with only the first seaming operation performed thereon in order that the seams produced thereby might be inspected.

It is another object of the present invention to

reduce the labor involved, and the time that the operation of this machine must be interrupted in order to accomplish the removal from a double seamer of a desired number of cans after the first seaming operation has been performed on these and without the second or flattening seaming operation having been performed.

The manner of accomplishing the foregoing objects, as well as further objects and advantages, will be made manifest in the following description taken in connection with the following drawings, in which:

Fig. 1 is a fragmentary, diagrammatic, side elevational view of a double can seamer in which is incorporated a preferred embodiment of the present invention.

Fig. 2 is a horizontal sectional view of Fig. 1, taken on the line 2—2 thereof.

Fig. 3 is a horizontal sectional view, taken on the line 3—3 of Fig. 1 and looking upward.

Fig. 4 is an enlarged, horizontal sectional view, taken on the line 4—4 of Fig. 1, this view illustrating a preferred embodiment of the novel second seaming operation control cam of the invention, the cam follower rollers of the can seamer being illustrated in broken lines in this view.

Fig. 5 is a fragmentary view similar to Fig. 4, and illustrates said second operation control cam in retracted position to render the second operation seaming rolls inoperative while a sample set of cans subjected only to the first seaming operation is processed and removed from the machine.

Fig. 6 is an enlarged, fragmentary, sectional detail view, taken on the line 6—6 of Fig. 4 and illustrating the cam retracting eccentric of the invention.

Fig. 7 is an enlarged, fragmentary, detail view, taken on the line 7—7 of Fig. 7 and illustrating the means for uniformly applying a yieldable pressure to the second operation seaming rolls and the unitary means for adjusting said pressure.

Fig. 8 is an enlarged, fragmentary, detailed sectional view, taken on the line 8—8 of Fig. 4 and illustrates the pivotal mounting of the yieldable, retractable cam for controlling the second seaming operation.

Fig. 9 is a fragmentary, horizontal, sectional view, taken on the line 9—9 of Fig. 6, and looking upwardly.

Referring specifically to the drawings, the invention is there shown as incorporated with a can double seamer 15. The construction of this general type of machine being well-known in the art, only those portions of the machine with which the invention is directly associated are illustrated in the drawings.

The double seamer 15 operates in accordance with the mode of operation described in the preamble of this specification and includes, of course, a stationary frame on which is fixed a stationary vertical shaft 16 about which a turret 17 rotates at a relatively low speed. This turret is connected by a tube 18, concentric with the shaft 16, with a table 19 which is also concentric with the shaft 16, and which carries a series of elevators which individually receive cans and elevate them into operative relation with the turret 17 and then withdraw downwardly to discharge said cans at the conclusion of each revolution of the turret about the shaft 16.

Mounted on the turret 17 is a series of can holding and rotating devices 25 which are equal in number to and vertically aligned with the ele-

vators of the table 19. Each of the devices 25 includes a can end chuck 26 which is adapted to fit within the panel of a can end so as to grip the latter. The chucks 26 continually rotate at a high speed so that when a can is received on an elevator on the table 19 and lifted with a can end superimposed thereon, to bring said can end into concentric engagement with the end chuck 26 thereabove, rotation of the latter is imparted to the can end and can. The upper element of each elevator being freely rotatable on the same vertical axis with the chuck 26 disposed thereabove, the can is caused to spin rapidly with the chuck 26.

Provided in the turret 17 adjacent each of the chucks 26 is a pair of vertical bores 30 fitted at their upper and lower ends with bearing sleeves 31, in which sleeves shafts 32 are journaled. The upper end 33 of each of these shafts is turned down and threaded to receive a nut 34. Fixed on the lower ends of the shafts 32 are arms 35 and 36, carrying seaming rolls 37 and 38, respectively. The first of these rolls forms the curling or first seaming operation; the second of these rolls forms the flattening or second seaming operation. Mounted on the upper ends of the shafts 32 (carrying seaming rolls 37) are arms 40 carrying cam follower rollers 41 which are disposed at a relatively high level on said arms. Mounted on the upper ends of the shafts 32 (carrying seaming rolls 38) are arms 42 carrying cam follower rollers 43 which are disposed at a relatively low level on said arms.

As may be noted in Fig. 2, each arm 40 has a finger 44 which extends toward a next adjacent arm 42 while that arm 42 has a finger 45 which is spaced from said finger 44 so that an expansion spring 46 placed between these fingers expands against the same and is held in assembled relation therewith by studs 47 extending from said fingers into the ends of said spring.

The action of the springs 46 is to rotate the shafts 32 to maintain the rollers 41 and 43 in rolling contact, respectively, with upper and lower cams 50 and 51 which are provided on a stationary cam plate 52 which is mounted on shaft 16 and is non-rotatably secured thereto by a key 53 (Figs. 4, 6 and 7).

The upper cam 50 includes a low section 54 and a high section 55, the low section 54 being substantially concentric with the shaft 16, while the radius of section 55 increases slightly in an anti-clockwise direction between one end and the other end thereof. As the cam 50 is followed by rollers 41, this cam controls the swinging of the curling or first seaming operation rolls 37 into seaming relation with a can being rotated by the adjacent chuck 26. It will thus be noted that each seaming roll 37 will be withdrawn from active engagement with said can, while its roller 41 is following low section 54 of cam 50, and will be shifted into seaming relation with said can as said roller 41 travels from cam section 54 onto cam section 55. The slight increase in height of the section 55 as the roller 41 thus progresses along this cam section merely shifts the seaming roll 37 further inwardly as is necessary with the progress in the first seaming operation performed by said roll.

Cam 51 includes a concentric low section 60 and a substantially concentric high section 61, the radius of which increases slightly in a counterclockwise direction.

Owing to the fact that cam follower rollers 43 follow cam 51, this cam controls the shifting of

flattening or second seaming operation rolls 38 into seaming engagement with the cans being spun by the adjacent chucks 26. While each roller 43 is traveling over the low section 60 of cam 51, the corresponding seaming roll 38 is withheld in spaced relation with its chuck 26; while the travel of said roller 43 onto section 61 of said cam swings said roll 38 into engagement with the curled or partly formed seam on the can being spun by said chuck so as to flatten and complete said seam.

As previously pointed out, it is necessary in performing the second seaming operation to provide an opportunity for each such seaming roll 38 to yield away from its chuck 26 during said second seaming operation whenever the thickened portion of this seam produced by an end portion of the straight can body seam, which is necessarily incorporated in each of the annular end seams, comes between said chuck 26 and said seaming roll 38. In the present invention, this opportunity is provided by yieldably mounting the cam section 61 of the cam 51. This mounting is accomplished in the following manner:

Cam section 61 is formed as a separate element from the cam plate 52, while the balance of cams 50 and 51 are integral with said cam plate. To facilitate said mounting, cam plate 52 is provided with a boss 62 (Fig. 8) having a bore 63 and a counterbore 64 at its lower end. This boss also has a pin hole 65. Formed on the cam section 61 is a hub 66 (Fig. 8) having a bore 67 of the same diameter as bore 64. A headed pivot pin 68 rotatably fits and extends through the bore 67 and into the bore 64. This pin has a hole 69 therein, which is adapted to be aligned with the hole 65 in the boss 62 so that a pin 70 may be driven into the holes 65 and 69 to prevent rotation of the pivot pin 68 in the bore 64. The pin 68 has a tapped central hole 71 into which a cap screw 72 is adapted to be screwed after this screw has been inserted downwardly through the bore 63 (Fig. 8).

The cam plate 52 also has a boss 75 (Fig. 6) which is bored to receive a bearing sleeve 76, which rotatably receives a heavy short shaft 77 having an annular groove 78 cut therein, a hexagonal head 79 formed on the upper end thereof, a laterally extending pin 80 provided therein, and an eccentric control shaft 81 extending downwardly therefrom into a sleeve 82 driven into a suitable bore provided to receive the same in a boss 84 formed on the cam section 61. Shaft 77 is held in place by a washer 86 extending into the annular groove 78 formed in said shaft, the washer 86 being fixed to the boss 75 by a screw 87 extending downwardly through said washer and screwing into a suitable tapped hole 88 provided in said boss. The head of screw 87 forms a stop for the pin 80 (Fig. 4) with the shaft 77 in one position, while a second screw 89 is screwed into a suitable tapped hole provided therefor in the boss 75 to form a stop for the pin 80 (Fig. 5) when the shaft 77 has been turned to an opposite operating position.

Referring now to Figs. 4 and 7, the cam plate 52 has a hub 90 having a horizontal tapped hole 91 (Fig. 7) in which a screw 92 is screwed, the head of said screw acting to retain one end of a coiled compression spring 93 in place against a face 94 of said hub 90. The cam section 61 also has a boss 95 which is disposed in parallel spaced relation with said face 94. Screwed into a threaded hole 96 in the boss 95, which hole is

in alignment with the hole 91, is a spring adjusting screw 97 having a head 98 against which the opposite end of said spring rests, this head having a boss 99 formed thereon which extends into said spring and, acting together with screw 92, retains this spring in place. The screw 97 is retained in its adjusted position by an Allen screw 100 which is screwed into a suitable tapped hole provided in the cam section boss 95.

Operation

From the foregoing description, it is manifest that the cam section 61 is adapted to swing about the pin 68, and that, when the eccentric shaft 81 is positioned as shown in Fig. 6, the spring 93 yieldably holds cam section 61 in its outermost position in which the sleeve 82 is pressed outwardly against the eccentric 81 (Fig. 6). The outer portion of sleeve 82 is spaced from the eccentric 81, however, indicating that the cam section 61 is free to yield inwardly a substantial distance when the pressure of any roller 43 against this cam section is sufficient to overcome the tension of the spring 93 as when the flattening seaming roll 38 connected with this cam follower roller 43 passes over a thickened portion of the annular seam it is operating upon. As clearly shown in Fig. 7, the screw head 98 is provided with radial holes 105 into which a rod may be inserted to rotate this screw and thus adjust the pressure imposed outwardly by the spring 93 against the cam section 61 and which must be overcome by the inward pressure thereagainst of a cam follower roller 43 in order to swing said cam section 61 inwardly about its pivot pin 68.

When one of the cam follower rolls 43 first rides onto the cam section 61, as shown at the upper right corner of Fig. 4, the flattening seaming roll 38 associated with said roller 43 is not swung far enough inwardly against the seam being formed to require relief when passing over an excessively thickened portion of the seam. As the roller 43 advances in a counterclockwise direction along the outer surface of cam section 61, however, the increasing radius of this cam section forces the corresponding second seaming operation roll 38 further inwardly towards the chuck 26 holding the can being worked upon. Thus, towards the conclusion of the second seaming operation, when roller 43 has come opposite the highest portion of the cam section 61 at the left end of the same, as shown in Fig. 4, the arrival of the corresponding seaming roll 38 opposite the excessively thickened portion of the seam being worked on will make it necessary for this roll 38 to yield in order to pass over said excessively thickened seam portion to avoid damaging either the machine or the can. This relief is provided in the present invention by placing the spring 93 opposite the left end of cam section 61 where the latter has its greatest radius from the axis of shaft 16.

It is thus seen that the present invention provides a way of applying substantially the same pressure against each seam through each seaming roll 38 in the second seaming operation throughout the entire length of said seam, and when said roll comes opposite the excessively thickened portion of the seam, at a time when this roll is applying its final flattening compression to the same, spring 93 permits this roll to yield and pass over said thickened portion without damage either to the can or to the machine. It is also to be noted that any changes found

necessary in this pressure may be accomplished by a single adjustment of a unitary adjusting means, thereby eliminating the necessity formerly met with of separately adjusting the relief means provided individually for each of the second operation seaming rolls 38.

The present invention also provides a simple means for retracting cam section 61 from its operative position, in which it is shown in Fig. 4, to an inoperative position, in which it is shown in Fig. 5, thereby rendering the flattening second seaming operation rolls 38 inoperative to accomplish the second seaming operation so that cans discharged from the machine while the cam section 61 is so retracted will merely have the curling or first seaming operation performed thereon, thereby permitting the inspection of this group of cans to determine whether or not the first or curling seaming operation is being satisfactorily accomplished.

The retraction of the cam section 61 is readily accomplished simply by applying a wrench to the hex-head 79 of the eccentric shaft 77 and rotating this from the position in which it is shown in Figs. 4 and 6 to the position in which it is shown in Fig. 5. When so rotated, the eccentric 81 operates on the sleeve 82 to swing the cam section 61 about its pivot pin 68 and shift said cam section into a retracted position, in which it is shown in Fig. 5, where it is seen that the left end of this cam section is disposed at a substantially lower radius than the right end portion of said cam section. It is thus clear that in its retracted position shown in Fig. 5 the cam section 61 renders the second operation seaming rolls 38 inoperative to flatten the seams which were partially formed in the curling stage or first seaming operation by rolls 37.

After a suitable number of cans have been passed through the machine to provide the necessary check on the manner in which the first seaming operation is being performed, a wrench may again be applied to the head 79 of the eccentric shaft 77 and the latter quickly returned to its normal position shown in Fig. 4, which will restore cam section 61 to its outward operative position thereby causing the flattening seaming rolls 38 to resume their performance of the second seaming operation on cans passing through the can double seamer 15.

What is claimed is:

1. In a can seamer, the combination of: a frame; a turret rotatable on said frame; a series of circumferentially spaced can holding and rotating devices mounted on said turret; a series of seaming rolls one of which is associated with each of said devices; means on said turret for pivotally mounting each of said rolls in shiftable relation with a can held in the device with which said roll is associated; a cam on said frame engaged by said roll mounting means, as said turret rotates, to shift said rolls successively into seam forming relation with said cans; means on said frame forming a pivot for said cam adjacent one end thereof to permit said cam to swing away from said roll mounting means into an inoperative position relative to the latter; a rotary control member pivotally mounted on said frame; an eccentric provided on said member and positioned relative to said cam to be engaged by the latter to limit the swinging of said cam about its pivotal mounting towards said roller mounting means; stops limiting rotation of said control member between two positions in the first of which said eccentric permits said cam to be

5 swung into an operative position relative to said roll mounting means, said eccentric, in moving to the second of said positions, shifting said cam from said operative position to said inoperative position; and spring means constantly pressing said cam against said eccentric.

2. A combination as in claim 1 including means for adjustably varying the pressure applied by said spring means to said cam.

3. In a can seamer, the combination of: a frame; a turret rotatable on said frame; a series of circumferentially spaced can holding and rotating devices mounted on said turret; a series of freely rotatable seaming rolls, one of which is associated with each of said devices; means on said turret for mounting each of said rolls in shiftable relation with a can held in the device with which said roll is associated; a cam shiftably mounted on said frame for movement between an operative position, in which said cam is engaged by said roll mounting means as said turret rotates thereby shifting said rolls successively into seam forming relation with said cans and an inoperative position in which said rolls are not so actuated by said cam; resilient means applying pressure to said cam urging said cam towards said roll mounting means; a stop engaged by said cam, thereby halting the movement of said cam in response to said resilient means when said cam reaches said operative position; and a control member rotatably mounted on said frame and having said stop eccentrically mounted thereon whereby a partial rotation of said control member will retract said cam from its operative position to its inoperative position, and whereby a reverse partial rotation of said member will return said cam from its inoperative position to its operative position.

4. In a can seamer, the combination: a frame, 40 a turret rotatable on said frame; a series of circumferentially spaced can holding and rotating devices mounted on said turret; a series of freely rotatable seaming rolls, one of which is associated with each of said devices; means on said turret for mounting each of said rolls in shiftable relation with a can held in the device with which said roll is associated; a cam shiftably mounted on said frame for movement between an operative position, in which said cam is engaged by said roll mounting means as said turret rotates thereby shifting said rolls successively into seam forming relation with said cans, and an inoperative position in which said rolls are not so actuated by said cam; and quick throw 45 means including an eccentric for controlling the shifting of said cam between said two positions, said last-mentioned means being movable in one direction with a short, quick movement for placing said cam in said operative position and being reversibly movable with a short, quick movement to shift said cam from said operative position to said inoperative position, whereby said cam may be temporarily rendered inoperative during the passage of a limited number of cans through said seamer for the purpose of testing the functioning of other parts of said seamer after which said cam may immediately be returned to said operative position for the resumption of the performance of said seaming operation thereby on cans passing through said seamer.

5. In a can seamer, the combination of: a rotary turret; a series of circumferentially spaced can holding and rotating devices mounted on said turret; a series of seaming rolls one of which is

associated with each of said devices; means on said turret for pivotally mounting each of said rolls in shiftable relation with a can held in the device with which said roll is associated; a cam engaged by said roll mounting means as said turret rotates to shift said rolls successively into seam forming relation with said cans; means for shiftable mounting said cam; resilient means applied to said cam and pressing the latter yieldably towards a precise position in which said cam is operatively related to said roll mounting means for engagement thereby as aforesaid; a control member positioned to positively limit the movement of said cam in response to the pressure of said resilient means towards said roll mounting means, to said precise operative position; means including an eccentric for quickly shifting said control member to retract said cam against the pressure of said resilient means to an inoperative position relative to said roll mounting means, and for thereafter reversely shifting said control member with equal facility to release said cam from said retracted position and allow said cam to return under the pressure of said resilient means to said precise operative position; a pair of stops limiting the shifting of said control member between two positions, in the first of which said control member is positioned to limit movement of said cam to its precise operative position aforesaid, the other position of said control member being reached when it has been shifted to retract said cam out of said operative position; and means for adjustably varying the force applied by said resilient means to said cam when the latter is in its operative position and with which said resilient means resists depression of said cam by said roll mounting means.

10

10

- 5 6. In a can double seamer, the combination of: a rotary turret; a series of circumferentially spaced can holding and rotating devices mounted on said turret; a series of curl seaming rolls one of which is associated with each of said devices; means on said turret for pivotally mounting each of said curling rolls in shiftable relation with a can end held in the device with which said roll is associated; a cam engaged by said curling roll mounting means as said turret rotates to shift said curling rolls into seam curling relation with said cans; a series of seam flattening rolls one of which is associated with each of said devices; means on said turret for pivotally mounting each of said flattening rolls in shiftable relation with a can held in the device with which said flattening roll is associated; a cam engaged by said flattening roll mounting means as said turret rotates to shift said flattening rolls successively into seam flattening relation with said cans, the latter operation following said seam curling operation; and quickly operable eccentric means for temporarily retracting said flattening cam a precise distance whereby said cam will not cause said flattening rolls to perform said seam flattening operation and cans passed through said seamer will be subjected to said seam curling operation alone, said eccentric means being quickly operable to return said flattening cam precisely to its original operative position.
